United States Patent Office

Des. 213,688
Patented Apr. 1, 1969

213,688

CEILING PANEL OR SIMILAR ARTICLE

Bernard J. Gaffney, Stillwater, Minn., assignor to Conwed Corporation, St. Paul, Minn., a corporation of Delaware

Filed Mar. 6, 1968, Ser. No. 10,876

Term of patent 14 years

Int. Cl. D25—01

U.S. Cl. D18—2

The figure is a plan view of a ceiling panel showing my new design which panel is of conventional thickness.

I claim:

The ornamental design for a ceiling panel or similar article, substantially as shown and described.
